CLAIM

The ornamental design for a container, as shown and described.

DESCRIPTION

FIG. 1 is a left, front, top perspective view of a container, showing my new design;

FIG. 2 is a right, rear, bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a left, front, top perspective view of the container of FIG. 1, with a handle of the container at another position; and,

FIG. 10 is a right, rear, top perspective view of the container of FIG. 1, with the nozzle of the container at an open position.

The broken lines in the drawings depict portions of the container that form no part of the claimed design.

1 Claim, 10 Drawing Sheets
